[57] ABSTRACT

A system for automated production of spark plugs, which comprises a first station for the production of insulators, a second station for the assembly of the central component of the spark plug, and a final assembly station; each station operates, at least partially, in continuous kinematic motion, and the transfer means between the stations comprises storage means. The system also comprises means for servo-control and synchronization of the stations, the parts, before their final assembly, being transferred in vehicles belonging to each station or part of a station.

SYSTEM FOR AUTOMATED PRODUCTION OF SPARK PLUGS

The present invention relates to a system for the automated production of spark plugs for internal combustion engines.

Present systems for mass production of spark plugs require a number of machines operating on a batch basis. Each machine produces or assembles the constituent parts of a spark plug; usually, a sub-assembly of part is first produced, then stored, and subsequently brought to another machine where additional operations are carried out, also on a batch basis. These systems, of very varied types, all have the disadvantage of giving relatively low production rates, being complicated, and requiring a relatively large amount of labor, as there are many handling operations between the machining and assembly machines.

The object of the present invention is to overcome these disadvantages. The invention provides a system for automated production of spark plugs at a high rate, which can be adapted to the production of a wide variety of types of spark plug by simple additions to or modifications of the constituent parts.

To this end, the invention relates to a system for the automated production of spark plugs, characterised in that it comprises a first station for the production of insulators, a second station for the assembly of the central component of the spark plug, and a final assembly station, each station operating at least partially in continuous kinematic motion. The transfer means between the stations comprises storage means; the system also comprises means for servo-control and synchronization of the stations, the parts, before their final assembly, being transferred in vehicles belonging to each station or part of station.

Under the invention, the system for automated production of spark plugs combines the advantages of a series of production stations operating in continuous motion, at a high production rate, with the avoidance of the disadvantages of a too rigid and complicated construction, by virtue of the transfer means between the stations. This transfer means comprises storage and synchronization means, allowing compensation for changes in the relative operating rates of the stations without interrupting operation of the overall system.

The system of the invention starts with a rotary insulator compacting mechanism, which produces a series of dense, compacted insulator blanks. These insulator blanks are transferred to an insulator machining drum that includes a mill. The forward machining speed of the mill is adjusted uniformly or proportionally to the mass of the matter removed, by means of a cam also used to compensate for wear of the mill. The machining drum is enclosed so that dust and other machining by-products are controlled and contained. These by-products are recovered for use in the fabrication of new blanks, for which purpose they can be returned to the hopper of the initial compacting drum. The mill of the machining drum can be dismantled rapidly to allow for effective maintenance operations conducted outside the machine.

The system utilizes a sintering machine which is separate from the compacting and machining apparatus; consequently, heat from the sintering machine does not adversely affect the compacting and machining operations. Because the duration of the sintering operation

is very much longer than that of the operations that precede it, the insulators are passed in parallel lines through several curing tunnels in order to obtain a sufficient output rate. Moreover, because the sintering machine is separate, special vehicles especially suited to heat treatment can be used in it; these vehicles are not necessarily identical with the vehicles used in the compacting and machining apparatus.

The completed insulators are transferred to a central component assembly station, in which the internal conductive components are assembled in each insulator and cemented in place. At the next and final station, the conductive holder is mounted on each central component, together with any required mounted gaskets and the like, finishing the complete spark plug manufacturing operation. The transport between the operating station allows for some differential in production rates without requiring system shutdown.

The system of the invention, some principal characteristics of which are enumerated above, produces spark plugs automatically at a high rate, but is not limited to any one type of spark plug, and can be adapted to different types very simply by changing or moving a working unit or a working drum. Since the parts, and particularly the insulators, are transported in vehicles, they are not subjected to wear or shock, which considerably reduces the number of plugs that are rejected. Another advantage of this method resides in the fact that since the insulator is not subjected to wear, there is no formation of abrasive dusts, which can cause rapid wear of the components of the machines and the system.

The present system will be described in greater detail with the aid of one embodiment of the invention, represented schematically, by way of non-limitative example, in the accompanying drawings in which:

FIG. 1 is a detailed view of a conventional spark plug, which can be produced by a system constructed in accordance with the invention;

FIG. 2 is a detailed elevational view of the central component of the spark plug of FIG. 1;

FIG. 3 is a schematic diagram of the whole of the system according to the invention;

FIG. 4 is an axial half cross-section of the insulator compacting drum;

FIG. 4A shows a detail of the compacting drum in the mold closure area;

FIGS. 4B, 4C, 4D show schematically the three stages of the operation of the compacting drum;

FIG. 5 is a detailed view of the axial cross-section of the insulator machining drum;

FIG. 17A shows the axial cross-section of the area in which the nut screwing drum is associated with the transfer drum that feeds it;

FIG. 17B shows a plan view of the same area as that in FIG. 17A;

FIG. 18 is a detailed axial cross-section of a sealing control drum.

The system of the invention provides fully automated manufacture of spark plugs for internal combustion engines. In general, and without the system being limited to any specific type of spark plug, the system may be utilized in manufacturing a conventional spark plug (FIG. 1) which comprises a central subassembly *a*, consisting (FIG. 2) of an insulator *b*, rotationally symmetrical, and having an axial opening into which an electrical connection rod *c* extends. The rod *c* is connected to an electrode *d*. The cement *e* forms this electrical connection and also immobilizes the rod *c* and seals the central subassembly or component *a*. The central component *a* is mounted in a metal holder *f* that is adapted to be screwed into the cylinder head of an engine. A seal between the holder *f* and the central component *a* is obtained at the upper part of the spark plug by means of an upper gasket *h*, pressed against the central component *a* by the crimp *l*. This seal is reinforced by a lower gasket *k*. In use of the spark plug, the holder *f* is screwed, so as to effect a seal, into the cylinder head of an engine, by means of a cylinder head gasket *i*. Lastly, a nut *g* is threaded onto the free end of the rod *c*.

FIG. 3 is a schematic diagram of the whole of a system or machine for the production of spark plugs similar to the plug described above in relation to FIGS. 1 and 2.

The system comprises an insulator-production station 1, constituted, in general, by an insulator compressing and machining machine 11 and a sintering machine 12. These two machines operate in continuous kinematic motion and are interconnected through a series of transfer drums.

The compressing and machining machine 11 comprises a compressing drum 111 which forms a stable insulator blank from a predetermined quantity of inorganic powder. The machining drum 112 machines this blank in order to give it a form approximating that of the final insulator *b*. (FIGS. 1 and 2). The machine 11 (FIG. 3) comprises a number of transfer drums 113, which transfer the blanks between the drums 111 and 112, as well as returning the vehicles receiving these blanks.

The insulator-production station 1 comprises, in addition, a sintering machine 12 which is supplied by a loading and transfer device 121, which brings the insulators into a sintering or curing tunnel 122 and then into a cooling area 123. Four curing tunnels 122 are shown in FIG. 3; a larger or smaller number may be provided, depending on the production rate of the system and other related factors.

The loading device 121 is an endless conveyor comprising a vehicle-loading component 1211 at the outlet point of the compressing and machining machine 11, a component 1212 for distributing the vehicles carrying the insulators to the curing or sintering lines passing through the respective curing tunnels 122. On emerging from the cooling area 123, there is a combining component 1212' similar to the loading component 1212 but operating in the opposite manner. This combining component 1212' combines the four lines of vehicles into a single line.

Lastly, an unloading component 1211' enables the sintered insulators *b* to be separated from the transfer vehicles which are brought back to the loading component 1210.

The insulators *b* thus manufactured in station 1 pass into a central component-assembly station 2. This station 2 comprises a central component-assembly machine 21 and curing station 22. The central component-assembly machine 21 comprises a certain number of working drums.

In the present case, the machine 21, shown in further detail in FIG. 6, comprises an insulator-introducing unit with a number of drums 210 and a distributor 219, in which the insulators *b* are placed in position in vehicles for transfer to the machine 21, a marking drum 211, where identification indicia and other marks are printed on the insulator, and a flaming drum 212 which dries the marking ink and pre-heats the insulator before its passage into an enamelling drum 213 which coats the insulator with enamel.

This assembly machine 21 also comprises an electrode-introducing unit, including a drum 214 and an electrode distributor 219', followed by proportioning and compacting drums 215, 215' for the cement, and a unit 216 for introducing the rods *c* comprising a drum 216 and a distributor 219''. Following this, the assembled part is checked in an assembly control drum 217. If the result of the check is satisfactory, the vehicle and the assembled central component *a* pass to the vehicle changing drum 218, in which the central component *a* which has just been obtained, leaves the vehicle of the

machine 21 and is brought into a heat-treatment vehicle V (FIG. 6H).

The machine 21 (FIG. 6) comprises a number of distributors such as the insulator distributor 219, the electrode distributor 219' and the connecting rod distributor 219''. These distributors, of known construction, are connected to the corresponding drums 210, 214, 216.

The check that is made in the drum 217 consists in checking the level of the head of the rod c. Thus, if any of the constituent components are defective or are not of the required size, the level required is not reached and the vehicle is diverted from its normal trajectory and ejected from the system.

The change of vehicle effected at the drum 218 is necessary because the central component a is to be cured. For, in the assembly machine 21, the vehicles are intended simply to support the insulator b during the assembly of the component a. The assembly vehicles are subjected only to mechanical stresses. However, during heat treatment, the vehicles V must be able to withstand temperatures of above 1,000° C but do not have to withstand any further great mechanical stresses.

The assembly vehicles of the machine 21 are recovered by the vehicle changing drum 218 and brought back to the introducing drum 210.

The heat-treatment vehicles V enter the assembly station 2 by passing through a synchronization device such as a helicoidal screw which brings them to the operating speed of the station 3 (FIG. 3). The empty vehicles V are brought back to the machine 21, if necessary, passing through a storage device such as the turning tables 225. On entering the machine 21, the vehicles are again synchronized in accordance with the speed of the machine 21.

These operations take place in various drums 211 to 217 and are shown schematically in FIGS. 6A through 6H.

FIG. 6A shows the insulator b being marked, FIG. 6B shows the insulator b being flamed or pre-heated, FIG. 6C shows the insulator b being enamelled, FIG. 6D shows the electrode d being introduced, FIG. 6E shows the cement e being introduced and compacted, and FIG. 6F shows the rod c being introduced. FIG. 6G shows the assembled but uncured central component a' being checked and FIG. 6H shows the vehicles being changed, that is, the assembled central component a' being transferred from the vehicle of the machine 21 to the heat-treatment vehicle V.

On leaving the assembly machine 21, the assembled central component a' with its vehicle V is conveyed to the curing station 22 (FIG. 3). This curing station 22 consists of a transfer device 221 which conveys the uncured central component a' and the vehicles V into an oven 222. Three ovens 222 are shown; again, the number of ovens may vary to suit the production rate and other requirements of the overall system. On leaving the oven 222, the components a are then conveyed to a pressing drum 223, and then to the final assembly station 3, having passed through the storage devices 224.

The pressing drum 223 cools the parts leaving the curing station 22 by means of forced convection and a given mechanical pressure. As an example, the pressing operation is carried out for a period of 10 seconds, which corresponds to the setting time of the cement e

under the heating conditions of the example. On leaving the drum 223 the parts are conveyed to the final assembly station 3. Dynamic storage devices 224 are provided between the assembly station 2 and the station 3 in order to compensate for any lack of synchronization between the station 2 and the station 3. These devices 224, for example, may comprise turning tables arranged in series. The reserves which they can carry are variable. In the particular case where the reserve is nil, the parts pass directly through the storage devices 224.

When the stations 2 and 3 are synchronized, it is advantageous to have the devices 224 half filled. If the station 2 stops operating, the station 3 can continue to operate until the reserves are exhausted. If the station 3 stops operating, station 2 can continue operating until the storage devices 224 have been filled. This allows limited shutdowns of either station 2 or station 3 without interruption of overall system operation.

Lastly, it is possible to servo-control the system so that the operating rate of the stations 2 and 3 is a function of the rate at which the storage devices 224 are filled.

The divider component 221 divides the single line of vehicles V coming from the assembly machine 21 into a certain number of parallel lines, for example, three, which pass through the respective tunnels 222 of the passage oven 22. On leaving these tunnels, a combining component 221, similar to the divider, but operating in the opposite manner, recombines the several lines again into a single line.

In the final assembly station 3, each central component a is separated from its heat-treatment vehicle V and the vehicle is returned at the vehicle-changing drum 218 of the assembly machine 21.

The final assembly station 3 assembles the central component a into the holder f, interposing the gaskets h, i, k, and screwing the nut g (FIGS. 7A-N).

The assembly station 3 (FIG. 7) comprises a unit for introducing the holder f including a drum 301 and a drum 302 for positioning the lower gasket k. Following this, a drum 303 is provided for inserting the central component a into the holder f provided with a lower gasket k. This partial assembly is controlled in a control drum 304 and the part then passes into the unit which positions the upper gasket h, comprising the drum 305. A drum 306 in the compacting unit places the whole into position and a cold crimping drum 307 in the crimping unit turns over the upper lip of the holder f, in order to hold the upper gasket h.

A heating drum 308 heats the holder and a drum 309 hot crimps the assembly. The connecting nut g is screwed onto the part that has been made in the screwing drum 310 of the unit for distributing the nuts g. The spark plug is then finished. A drum 311 adjusts the electrode and a drum 312 checks the seal of the spark plug.

Lastly, in the last stage, a drum 313 positions the cylinder head gasket i and a drum 314 checks the dielectric properties of the spark plug.

The final assembly station 3 comprises a distributor 315 for the holders f. A distributor 316 of the lower gaskets k cooperates, respectively, with the drums 301, 302. A distributor 317 sends the upper gaskets h to the drum 305 and a distributor 318 sends the connecting nuts g to the drum 310.

A distributor 319 sends the cylinder head gaskets to the drum 313. Between the various drums 302, 303, 304, 305, 306, 307, 308, 309, 310, 311, 312, 313, 314, there are transfer drums 320.

When one of the control drums 304, 312, 314, detects a defective part, the latter is eliminated by a discharge device 321.

In general, in the assembly station 2 for the central component *a* and in the final spark plug assembly station 3, the working drums and the transfer drums are for the most part combined in groups of two on one detachable mounting plate. This enables the drums or working units carrying out a particular operation to be replaced by different devices, if the construction or the form of the spark plug or the number of operations to be carried out are changed.

The various components constituting each operating station are described in some detail hereinafter. However, when these stations comprise identical or analogous components, the description of the components is not repeated in each case. This also applies to the general constitution of a working drum, operating in continuous kinematic motion. The general description of such a drum and of the control and driving means is made with reference to the compacting drum 111.

In general, (FIG. 4), the compacting drum 111 comprises a vertical rotary driving shaft *a*₁. This vertical shaft is driven from a horizontal shaft *a*₂ by means of a toothed crown wheel *b*₁ and a conical pinion *b*₂. The shaft *a*₁ carries a circular plate *c*₁ provided with recesses *c*₂ on its periphery. The shape of the recesses corresponds to that of the vehicles *V*, each of which receives a blank *b'* (or other part for other drums) to be worked upon in the drum. The operation to be carried out in each drum is effected while the latter is rotating. The stages of the operation are controlled during the rotary movement and in accordance with the angular position of the corresponding recess *c*₂. In general, each recess is associated with the tools required to carry out a specific operation. These tools rotate with the drum. The work is carried out in general with the aid of an upper tool *d*₁, which is movable with respect to an upper plate *d*₂ but is rotated by the plate *d*₂. The plate *d*₂ is rotated by the shaft *a*₁. In general, each drum also comprises a lower tool *e*₁, rotated by the plate *c*₁. The vertical shaft *a*₁ of the drum turns about a central column *f*₁, which is integral with a frame *g*₁. The frame *g*₁ also carries a fixed upper cam *h*₁ which controls operation of the upper tool *d*₁ (for example, its vertical translation) and a lower cam *j*₁, which controls the lower tool *e*₁ in a similar manner. In the particular case of the compacting drum 111, a hopper 1111 is provided to receive the powder for making the blank *b'*. The powder used can, for example, have the following composition by weight:

alumina	92 to 99%
wax	0.5% max.
talc	0.5% max.
clay	0 to 7%

The hopper 1111 is fixed rotatively with respect to the frame *g*₁. On the other hand, it can be adjusted vertically with the aid of a control wheel 1112, which, by means of a transmission screw and a peripheral wheel, actuates a regulating screw 1113, vertically displacing the nut 1114, which is connected to the hopper 1111 by means of an axle 1115.

The open bottom of the hopper 1111 rests on a tray 1116, which accompanies the hopper in its vertical movements, but which, in contrast, is connected to the drum for rotation therewith. A further tray 1117, which also is connected to the drum for rotation, but is not movable vertically, is located below the tray 1116.

A series of rings 1118 are carried by the tray 1116 and project into a series of bores 1119 in the tray 1117 in which they can slide. The rings 1118 define, in combination with the bores 1119, a series of proportioners located respectively in each of the vertical planes of the recesses of the drum. The bottom of each of the proportioners 1118-1119 is closed by a tray 11101, which is fixed during rotation. This tray 11101 is provided at its circumference, with an opening 11102 which, at the appropriate moment, connects the proportioner 1118-1119 with a channel 11103 emerging into a mold 11104.

The proportioner 1118-1119 operates in the following way:

After the internal volume of the proportioner has been adjusted to a suitable figure by vertical displacement of the tray 1116 with respect to the tray 1117, with the aid of the wheel 1112, the proportioner 1118-1119, driven rotatively by the drum shaft *a*₁, fills up with powder by passing under the hopper 1111. The powder is then levelled by the upper edge of the ring 1118 engaging the lower edge of the outlet of the hopper 1111, when the proportioner leaves the latter. The drum continues to rotate, until the proportioner 1118-1119 reaches a point above the opening 11102 of the tray 11101, which enables a measured amount of powder to pass into the mold 11104 by passing through the channel 11103.

The male part of the mold comprises a needle 11105 incorporated in the upper tool *d*₁. This needle 11105 is movable vertically in the axis of the lower mold 11104 and forms the axial aperture of the insulator *b*, and closes the mold during compression.

After the introduction of the powder to be compacted into the mold 11104, the needle 11105 of tool *d*₁ is lowered while the drum is rotating, by means of the cam *h*₁, until it is in the position shown in FIG. 4A.

The mold is then closed and is then in the compacting position. To effect the compacting operation, a fluid is conveyed under pressure into an annular chamber 11106 of the mold 11104. The fluid under pressure is provided by an isostatic pressure generator 11107. This pressure generator 11107 is a lifting jack controlled by the lower cam *j*₁ during the rotation of the drum.

When in the compacting position, the annular enclosure 11106 swells, and isostatically compresses the contents of the mold 11104. Thus the inner wall of the annular enclosure 11106 is deformable, while the outer wall is rigid.

The various operations above, that is to say, introducing the powder into the mold 11104, lowering the needle 11105, conveying the fluid under pressure into the annular enclosure 11106, are all controlled by the rotation of the drum 111 and its shaft *a*₁. The various stages are shown in detail in FIGS. 4B, 4C and 4D. FIG. 4B shows the mold 11104 open, the needle 11105 being in the waiting position above the mold 11104. This figure also shows the construction of the annular enclosure 11106. This enclosure is delimited on its exterior by a stiffener 111061 which is undeformable under the working pressure and a deformable inner

liner 111062. The fluid under pressure is introduced between the stiffener and the liner, after the needle 11105 has been positioned, as is shown in FIG. 4C.

The isostatic pressure in the enclosure is set at 300 bars. It is produced by a generator which is powered by a fixed cam. The pressure is maintained constant by a power limiter interposed between the cam and the generator.

The pressure of the fluid is maintained for about three seconds; decompression takes place in accordance with a rate determined for the non-destruction of the blank: duration—about 1.5 seconds.

The piston disengages, thereby opening the mold. The blank obtained is held by the needle and rises with the piston to an elevated position, as shown in FIG. 4D.

A detaching device 11108 for detaching the blank acts in the elevated position. The blank *b'* is made to rotate slightly around the needle 11105 and at the same time a vertical downward movement extracts the blank from the needle.

The blank *b'* is received by a unit vehicle which, under conditions suited to the fragility of the part, transfers it to the machining drum.

The transfer drums 113 (FIG. 3) take charge of the vehicle and the blank *b'* to convey it to the machining drum 112. During this transfer, the vehicle and the blank which it carries are turned 180° about a horizontal axis, in order to place the blank in a position suitable for machining.

The machining drum 112 for machining the blank *b'* is shown in detail in FIG. 5, which is an axial half section. FIGS. 5A and 5B show two of the machining stages.

The drum 112 comprises a double tray 1120 driven at the same speed as the machine 11. Between the two levels of the double tray 1120, there is a mill 1121 for machining the blank *b'*. This mill 1121 is driven rotationally around the same axle as the double tray 1120, but at a different speed. The mill is powered by a motor 1126 and a multiple set of belts 11261, shown schematically in FIG. 5.

After the blank *b'* has been transferred to the drum 112, the blank is extracted from the vehicle *V'* with the aid of a pusher 11231, controlled by a lever 11231a, controlled by a cam. The cam is then fixed, while the pusher turns with the drum.

At the same time as the pusher 11231 disengages the blank *b'*, this latter comes onto a needle 1122 which carries the blank *b'* until the milling operation has been completed.

The needle 1122, which engages in the central axial aperture of the blank *b'*, is parallel to the rotational axis of the mill 1121. This needle is integral with an accessory 11221 pivoting about an axis parallel to the needle. The pivoting movement is controlled by a cam 11222. The progressive pivoting movement brings the blank *b'* into the mill 1121, during the rotation of the double tray 1120 about the mill. In order to ensure that the blank *b'* is milled uniformly, the blank is rotated about its own axis by means of a driving belt 1124 shown in FIG. 5A and by passing over a series of pulleys 11241 (FIG. 5).

The belt moves at uniform speed and is inclined with respect to the base of the blank *b'*, so as to push the blank *b'* in the direction of the base of the needle 1124 in order to maintain it in position.

At the beginning of the trajectory of the blank *b'*, the distance between the needle 1122 and the axis of the drum 112 is at its maximum, whereas at the end of the machining operation, this distance is at a minimum, and the blank has the form of the machined part *b* (see FIG. 5A).

At the end of the machining operation, a chamfering tool 11232 (FIG. 5) is actuated by the lever 11232a, the free end of which carries a roller controlled by a cam when the drum 112 is rotating. This tool makes a chamfer in the upper orifice of the blank *b*.

To protect the system against dust and other by-products formed in machine 21 during the machining operation, drum 112 is equipped with a number of sealing gaskets such as the gasket 11201, for example, between the mill and the double tray. In addition, the drum is provided with a cover 11202 and the lower part also comprises a double gasket 11203, between the tray 1120 and the frame of the machine.

The stages in the machining operation in drum 21 are shown in FIGS. 5A and 5B. FIG. 5A shows the blank *b'* being machined and its final form *b*. FIG. 5B shows the machined insulator body *b* being mounted in a vehicle. The disengagement of the needle 1122 and introduction of the insulator body into the vehicle are effected by an extraction fork 1125, which executes a vertical movement with respect to the drum. This movement is controlled by a cam which is fixed during the rotation of the drum 112.

The drum 112 should be provided with a means of evacuating the milling dusts. These means may be conventional and are not shown.

On leaving the machining drum 112, the vehicle carrying the insulator body *b*, is conveyed to the transfer device 121 of the sintering machine 12 (FIG. 3). At the outlet of the machine, in the vehicle changing device 1210, the blank *b* leaves the vehicle linked to the machining and compacting machine 11 and enters a heat treatment vehicle, linked to the sintering machine 12.

The units and the drums of the assembly machine 21 for assembling the central spark plug component *a* are described hereafter with reference to FIG. 6. In this connection, only the new components of each drum are described, and not the traditional components such as circular trays, recesses, driving means, etc. The description is also limited, in general, to the tools corresponding to a single recess. It is evident that each drum comprises as many tools or groups of tools as it has recesses.

Since the various drums 210 for introducing the insulators *b* are identical, only one of these drums will be described hereafter. As indicated in FIG. 6, the four drums 210 are linked by transfer drums. Since there are four drums 210, the number of insulators distributed to each drum 210 is equal to one quarter of the number of the recesses of the drum, so that on the last drum 210, all the recesses are occupied by vehicles, each provided with an insulator *b*. The introducing drum 210 (FIG. 8) comprises a tube 2101 which successively delivers the insulators *b*. These insulators *b* are distributed in synchronous relationship with the vehicles by means of two separators 2102 and 2103 mounted pivotally about an axle 2104, which is integral with the drum. These two separators are controlled respectively by the cams 2102' and 2103'. The movement of these separa-

tors is clearly shown in FIGS. 8A and 8B, which also show the insulators *b*.

A spring 2105, not shown in detail, pushes against each separator so as to press it against its guide cam. With this turning tube arrangement, the movement of the insulators *b* can be readily accelerated from zero speed to the speed at which the vehicles pass through the machine 21.

The first transfer drum 210 brings the vehicles and the insulators *b* to the marking drum 211 (FIG. 6) where the required indicia are printed onto the insulators. Details of the marking means in the drum 211 are shown in section in FIG. 9.

The marking drum 211 (FIG. 9) comprises a tray 2110 with recesses which receive the vehicles carrying the insulators *b*. There is a lower tool which comprises a shaft 2111 for rotating the tray 2110. This shaft carries an auxiliary shaft 2112 mounted in the bore of the first shaft with the aid of ball-bearings, which enables it therefore to turn freely with respect to the shaft 2111. The auxiliary shaft 2112 comprises a pusher 2113 which is integral with it during rotation and movable in translation under the action of a spring 2114, which bears on the shoulder of the pusher 2113 and on the upper edge of the auxiliary shaft 2112. A gudgeon 2115 prevents the pusher from being ejected completely.

The lower shaft 2111 is controlled in vertical translatory motion by means of a cam.

An upper tool incorporated in the marking drum 211 comprises a shaft 2116 which rotates with the tray 2110, and is above to turn freely about its axis. This shaft 2116 terminates in a needle 2117 for engaging in the axial aperture of one of the insulators *b*.

During rotation of the drum 211, fixed cams control the raising movement of the shaft 2111, which vertically disengages the needle 2117. The pusher 2113 bears on the lower part of the insulator *b* under the action of the spring 2114. The accessory, formed by the shaft 2116, the insulator *b*, the pusher 2113, and the auxiliary shaft 2112, is rotated by engagement with a marking pad 2110' on a printing drum 211'. The marking operation is effected, by contact, in the traditional way.

The printing drum 211' comprises marking pads which are distributed on the periphery in a number corresponding to that of the recesses in the tray 2110 carrying the insulator-bearing vehicles. These marking pads 2110' are supplied with ink by an ink supplying device 211'', shown schematically in FIG. 6. This device, for example, can be a belt which takes ink from an inking cylinder immersed in an ink reservoir.

After having been marked, the insulator *b* is again introduced into the vehicle and it then passes to the flaming drum 212 (FIG. 6) where the print is dried and where the insulator is pre-heated prior to being enamelled.

According to one embodiment, the flaming operation is carried out by means of two gas tube burners on both sides of the circular path of the vehicles and of the insulators *b* on the drum. The vehicle is then transferred to the enamelling drum 213 (FIGS. 6 and 10).

As shown in FIG. 10, the enamelling drum 213 comprises a tray 2130 carrying the vehicles and the insulators *b*. The assembly includes a lower tool including a needle slide piece 2131 which, actuated by a pusher 2134, bearing on a fixed cam, disengages the insulator

b from the vehicle and brings the insulator to the level of an enamelling nozzle 2135, which rotates with the tray 2130. In order for the enamelling to be uniform, the pusher 2131 is driven rotatively by means of a pulley 2132 which it carries and a belt 2133.

The enamelling drum 213 is enclosed by a housing 2136 to collect the enamel spray and the noxious vapors.

The enamelling nozzle 2135 pumps the enamel from a tube 2137 that extends into a vessel 2137'. The nozzle is supplied with compressed air by a distributor 2138 and a tube 2138'.

When the enamelling operation has been completed, the insulator *b* is again introduced into the vehicle and conveyed to the electrode-introducing drum 214 (FIG. 6).

The drum 214 for introducing the electrode *d*, shown in some detail in FIG. 11, comprises fixed rails 2140 which bring the electrodes *d* along a path to a point near the center of the drum 214. The hub 2141 of the drum comprises recesses (FIGS. 11A, 11C) for extracting the electrodes *d*, one by one, from the rails 2140 and bringing them to the acceleration means. These acceleration means comprise a combination of a fixed tray 2142 in which a helical guide 2142' is formed (FIGS. 11 and 11D). This helix guides the upper part of each electrode *d*.

Displacement of the electrodes *d* along the path defined by the helix 2142' is effected by the tray 2143 of the drum 214. This tray, on one hand, has recesses, which are not referenced, provided with vehicles containing the insulators *b*, and on the other hand, radial corridors 2144 which go up to a point above the axis of the recesses. FIGS. 11 and 11A show vertical sections of such a radial corridor. The distribution of these corridors is shown in greater detail in FIG. 11D, which shows the electrodes *d* which are at the intersections of the radial corridors 2144 and the spiral ramp 2142'. The radial corridors terminate in a funnel-like orifice 2144' located above the insulator *b* and coaxial with it. When the electrode *d* reaches the level of this orifice 2144', it falls into the orifice of the insulator *b* (FIG. 11) and finds itself at the bottom of the latter.

FIG. 11A, which is a detail side view taken from FIG. 11, shows the superposition of the various passages of the hub 2141a, b, c, emerging in the corridors 2144. To provide an easier passage for the electrodes *d* between the supply rail 2140 and the guiding means of the hub 2141, which latter overlap, the passages are made on three levels, 2141a, b, c.

FIG. 11D is a schematic plan view showing the design of the corridors 2144 and of the helixes 2142'.

FIG. 11B is a view, on an enlarged scale, of the end of the helix 2142'.

Following this, insertion of the electrodes *d* in drum 214, each vehicle and insulator *b* is conveyed, in sequence, to the cement proportioning and compacting drums 215 and 215' (FIG. 6). These two drums successively effect the same operation, in order to proportion and compact the cement in small quantities. Such a drum is shown in FIG. 12. FIG. 12A, which is a simplified section drawn to a different scale, is intended to make the explanation simpler.

The drum 215 comprises a hopper 2150 which rotates with the drum. The bottom of the hopper comprises drilled holes corresponding to each recess of the drum.

A scraper 2151, fixed during rotation, is pushed against the bottom of the hopper 2150 by resilient upright pieces 2151' and brackets 2151''. The scraper 2151 is in the form of an arc of a circle, centered on the axle of the drum, its width being slightly greater than that of the orifices 2152. This scraper masks a part of the orifices 2152 during the rotation of the drum and, consequently, of the hopper 2150.

The cement proportioning device comprises a piston 2153 which is movable vertically. This piston is controlled by an accessory 2153' cooperating with a cam 2153'' in the traditional way. The piston 2153 carries a needle or rod 2154. The piston slides in a socket 2156 and the rod 2154 slides in the lower part 2156' of this socket. Lastly, the bottom of the socket is enclosed by a hopper 2155.

The drum 215 includes a lower tool comprising a pusher 2157 having an internal bore 2158. By means of a vertically movable accessory 2157'' and a spring 2157' (not shown in detail), a fixed cam 2159 acts on the pusher 2157, so that it raises the insulator *b* and pushes it resiliently into a conical opening 2155' provided in the lower part of the hopper 2155.

The proportioning of the cement and its introduction into the insulator *b* is effected in the following way:

The insulator *b* having been resiliently inserted, as explained above, into the opening 2155' in hopper 2155, the piston 2153 comes into a first portion so that its upper surface is level with the upper level of the orifice 2152. The piston 2153, having a section corresponding to that of the socket 2156, has a cut part 2153''. The volume *Q* included between the upper surface of the orifice 2152, the side wall of this orifice 2152, and the cut face 2153, corresponds to the quantity of cement to be introduced. When, during rotation, the upper orifice 2152 is no longer in contact with the scraper 2151, cement stored in the hopper 2150 falls into the space *Q* and fills it. The drum 215 continues its movement until the orifice 2152 is again under the scraper 2151. At the moment, the cam 2153'' actuates the movable accessory 2153', lowering the piston 2153 and bringing it to a second position, the position shown in FIG. 12. At that moment, the cement slides along the cut face 2153''' and reaches the hopper 2155, and then falls into the interior of the insulator *b*. The piston 2153 continues its downward movement and the needle 2154 descends into the inner cavity of the insulator *b* in order to compact the cement.

Following this, the piston 2153 and the needle 2154 return to their upper position, the insulator *b* is disengaged from the lower part of the hopper 2155, and the various components are then ready for a new cycle.

If, during the proportioning cycle of the cement, described above, it should happen that a recess of the drum 215 is not provided with an insulator *b*, the measured amount of cement falls through the empty vehicle and the bore 2158 into a discharge spout 2157''''.

The drum 216 (FIG. 13) for inserting the rods *c* into the insulators *b* comprises a central tray carrying the vehicles and the insulators. This tray is not shown. A distributor tube emerges vertically to each recess and coaxially with the insulator. This distributor head of the drum is shown in FIGS. 13 and 13A.

The connecting rods *c* are brought to the drum 216 in a line between two distribution rails 2160. These rails terminate near the axle of the drum. This is where

the hub 2161 of the drum has a series of extraction recesses 2161' (FIG. 13A). Each of these recesses receives a rod *c* and extracts it from the rail 2160, allowing the rod *c* to fall vertically into a funnel 2162 leading to a corresponding distributor tube 2163. Each of these tubes emerges above an insulator *b*.

This drum 216 thus comprises a number of distributor heads 2163 and recesses 2161', which number is identical with that of the number of recesses in the central tray carrying the insulator-bearing vehicles. On leaving the drum 216, the central component *a* thus assembled from an insulator *b*, electrode *d* and rod *c* is checked in the drum 217 (FIG. 6) and the components *a* which satisfy the conditions imposed are conveyed to the drum 218, which recovers the vehicles of the machine 21 and places the assembled component *a* into a heat treatment vehicle.

After heat treatment in the curing station 22, the component passes to the pressing and cooling drum 223, where an upper pusher and a lower pusher maintain the rod *c* against the electrode *d* under slight compression while the cement *e* is setting.

The heat treatment vehicles carrying assembled components *a* are then conveyed to the final machine 3. In this machine, the heat treatment vehicles are recovered and, contrary to that which was provided in the assembly machine 21, the component *a* travels from one drum to another without being supported by a vehicle. At this stage of manufacture, the mechanical strength of the component *a* is sufficient to prevent any damage from occurring during the transfer operations.

The component *a* next reaches the inserting drum 303 (FIG. 7) which, by means of the drums 301, 302, 320, also receives holders *f*, provided with a lower gasket *k*. The holders *f* are conveyed by the drum 301 to the drum 302 for positioning the lower gasket *k*.

The holders *f* are distributed by a centrifugal distributor emerging in a three-line apportioner 301' (FIG. 7). An escape device similar to that shown in FIGS. 8, 8A, 8B is provided at the end of each line to furnish a holder to every third recess in the drum 301. The holders are then conveyed to the drum 302, a detail of which is shown in FIGS. 14, 14A and 14B.

The drum 302 for positioning the lower gasket *k* comprises a central tray 3020 carrying the holders *f*. A fixed ramp 3021 conveys the gaskets *k* in a line to a given point on the trajectory of the holders *f* (FIG. 14A, 14B). At that level, the ramp 3021 is prolonged by a second ramp 3022 in the form of an arc of a circle, with the same radius and the same center as the circular trajectory of the holders *f*. A driving needle 3022', which is coaxial with the holders, and vertically movable, is brought downward by a pusher 3023' cooperating with a fixed cam during the rotation of the drum 302. The needle 3022 projects into the gasket *k* and guides it along the ramp 3022. At the end of this ramp, the lowest point of the needle 3022' is already in the central aperture of the holder *f* (FIG. 14B), and the gasket *k* can then fall to the bottom of this holder, but remains under the guidance of the needle 3022' during the falling movement. In order for the gasket to be positioned correctly at the bottom of the holder *f*, the needle descends completely into the latter, as is shown on the left-hand side of FIG. 14B. When this positioning operation has been completed, the fixed cam causes the needle 3022' to disengage.

The holder *f* then passes to the transfer drum 320 and then to the drum 303 where it receives the central component *a* (FIG. 7). The unit thus formed is checked in the control drum 304. Defective units are eliminated by the ejection device 321, and the correct parts pass to the drum 305 where the upper gasket *h* is placed into position. This drum 305, which is analogous to the drum 302, will not be described in detail.

The spark plug assembly *f, a* then passes to the compacting drum 306 (FIG. 7). The compacting drum 306 (FIG. 15) comprises a lower tool 3060 and an upper tool 3061 which are coaxial with the assembly of the holder *f* and the central component *a* present in the corresponding recess in the central tray 3062 of the drum. The lower tool and the upper tool are controlled in vertical translation by fixed cams which are not shown in detail. For the compacting operation, the lower tool 3060 raises the unit by acting upon the shoulder of the holder *f* while the upper tool, in the form of a cylindrical sleeve, caps the upper part of the central component *a* and bears with its bevelled edge on the upper gasket *h* in order to compact the component *a* into the holder *f*. At the end of this operation, the upper tool 3061 disengages from the component *a* and the lower tool 3060 brings back the assembly *f, a*, to the recess in the drum. This assembly *f, a* is then conveyed to the crimping drum 307 (FIGS. 7 and 16), the construction and operation of which are similar to those of the compacting drum 306. This drum 307 comprises a lower tool 3070 and an upper tool 3071, both movable in translation, along an axis common to the axis of a component *f, a* which has just been compacted.

The rotation of the drum 307 controls the vertical movements of the lower tool 3070, by means of a fixed cam, as before. This tool 3070 engages the assembly *f, a* in a guide groove of a plate 3073, so that the shoulder of the holder *f* comes to bear on the edges of this guide ramp. The tool 3071, in the form of a cylindrical sleeve, then caps the upper part of the central component *a* and bears on the upper crimping lip of the holder *f*. The holder *f* and the component *a* are thus crimped together.

The compacting operation is intended to consolidate the previously assembled components and initiate the shaping of the gaskets *k* and *h*. Considerable force, of the order to 1,000 daN, is exerted. This force is limited by known means, such as a calibrated, resilient device, consisting of "Belleville" or similar springs.

The cold crimping operation of the upper flange of the holder *f* requires a high pressure of the order of 5,000 daN.

After this operation, the holder is heated to about 800° C in the drum 308 (FIG. 7). This heating is intended to enable a shaping operation to take place easily in the hot crimping drum 309. The holder can be heated by any means, particularly electric means, such as induction heating. Such means, which are known, are not described in detail.

The hot crimping operation is then carried out in the drum 309, which is similar in all respects to the cold crimping drum 307. The hot crimping pressure is lower than the cold crimping pressure. In the present example, a pressure of the order of 3,000 daN is involved.

After these various operations, the nut *g* is screwed onto the spark plug. This operation is effected in the

drum 310, which cooperates with the connecting nut distributor 318. A working station of the drum 310 is shown in FIGS. 17, 17A and 17B.

The distributor (FIG. 7) brings the nuts *g* in a line but without orienting them. In order to orient them, a drum with pins picks up the nuts, one by one, on the basis of the dissymmetry of their ends. The nuts *g* which are not picked up by the pins are considered as being correctly oriented for screwing. These nuts are brought through a single vertical tube, not shown, which opens out onto an auxiliary drum 310'.

In order to transfer a nut *g* from the auxiliary drum 310' to the screwing drum 310, this latter comprises, as is shown in particular in FIGS. 17A and 17B, as many levers 3101 as there are recesses. These levers 3101 can pivot about their vertical axes and retract slightly, as described above. The thickness of the lever corresponds to the thickness of the cylindrical part of the small diameter of the nut, the double conicity of upper part of the nut coming to rest against the upper edge of the cylindrical cavity in the lever 3101. After the nut *g* has been transferred to the drum 310, a guide needle 3102 descends and is inserted into the nut *g* (FIGS. 17, 17A0, and pushes in the latter, to bring it onto the threaded end of the rod *c* of the spark plug. During this forced movement, the nut *g* pushes aside the lever 3101. When the nut *g* is in position on the threaded end of the rod *c* (FIG. 17), the drum 310 causes the screw head 3101 to rotate.

FIG. 17 shows details of the resilient assembly of the screw head, as well as the mounting of the pivoting lever 3101.

After the nut *g* has been screwed on, the spark plugs are transferred to the electrode regulating drum 311 (FIG. 7) and then to the sealing control drum 312 shown in FIG. 18. This drum 312 presses the holder *f* of the spark plug into a cavity 3180 with the aid of a vertically movable pusher 3181. A predetermined pressure is generated in this test cavity 3180 by passing compressed air through a check valve 3182 and a duct 3183, into the cylinder 3184. A pressure multiplier cylinder 3185 is actuated in translation and passes compressed air into the testing cavity 3180. A manometer connected to cavity 3180 may be employed to determine whether there is a seal defect in the spark plug being tested.

If the spark plug is not sealed, the pusher 3181 seizes it and, at a certain point of its course, not shown, the ejector 3186, sliding in the pusher 3181, ejects the plug above the evacuation device.

After this check, the plug passes to the drum 313 (FIG. 7) that places the cylinder head gasket *i* into position. This toric gasket is first threaded onto the holder and is then made fast by slight crushing. This drum 313 resembles in all respects the various other drums (302, 305) for putting the other gaskets into position.

A second check, namely a dielectric check, is made by the drum 314. After this operation, the plug leaves the final assembly station 3 and is conveyed to a packaging facility.

As an example, a machine has been produced, which manufactures six plugs per second operating at a normal speed and eight plugs per second operating at maximum speed, which corresponds to an hourly production of 22,000 plugs.

The system according to the invention is completely automated and the only external action required is the

introduction of the assembly components (rods *c*, electrodes *d*, holders *f*, etc.) that are not produced by the machine. This external action remains very limited, since the distributors of the parts and the compacting machine comprise hoppers which can hold a large number of parts or mixtures for the production of the insulator.

Lastly, as has already been indicated above, this system enables plugs of various types to be produced, simply by replacing, adding or moving working units consisting of drums. This covers not only modifications of the form and size of parts, but also of the number of parts constituting the spark plugs.

Although a preferred embodiment of the invention has been described, many variations and modifications will be apparent to those skilled in the art. Therefore, this invention is to be limited, not by the specific disclosure herein, but only by the appended claims.

I claim:

1. A system for automated production of spark plugs comprising:
  - a first insulator-production station, comprising insulator compressing means for forming insulators of compressed particulate dielectric material, machining means for shaping insulators and sintering means for sintering the insulators;
  - first transfer means for transferring the sintered insulators to a second station;
  - a second component-assembly station for receiving the sintered insulators from the first station and assembling central spark plug components, comprising means for inserting at least one electrically conductive elements into each insulator, together with a heat-curable cement, and curing means for subjecting the assembled insulators, conductive elements, and cement to heat to cure the cement and form complete central spark plug components;
  - second transfer means for transferring the central components to a third station;
  - and a third final assembly station for receiving the central components from the second station and assembling completed spark plugs, comprising means for mounting each central component in a conductive holder;
  - each of the first, second, and third stations operating at least partially in continuous kinematic motion;
  - at least one of the transfer means including storage means to compensate for limited differences in production rates in the two stations it interconnects;
  - and the parts of the spark plugs, prior to final assembly, being transferred within each station in vehicles which remain in the station and are not transferred to any other station.

2. A system according to claim 1, in which the insulator-production station comprises a compressing and machining machine for receiving a dielectric ceramic powder of which the insulators are composed, compressing the powder to form insulator blanks, and machining each blank into the shape desired for an insulator.

3. A system according to claim 2, in which the compressing and machining machine comprises a compression drum receiving the powder for the insulator and compressing it into the insulator blanks, a machining drum receiving the insulator blanks and machining each blank into the finished form of an insulator, and

a series of transfer drums linking the compression drum to the machining drum for circulating a multiplicity of vehicles between the compression drum and the machining drum, each vehicle carrying an insulator blank from the compression drum to the machining drum and returning empty to the compression drum.

4. A system according to claim 3, in which the compression drum comprises a fixed hopper for storing sufficient powder to form a multiplicity of insulator blanks, a rotary tray revolving with the drum, a series of adjustable proportioners each comprising a mold having deformable walls, a needle insertable into each mold to form an internal cavity in an insulator blank formed in the mold, an isostatic pressure generator communicating with the deformable walls of the molds to exert a given isostatic pressure, corresponding to the required pressure in the mold, a rotary transfer tray having a series of recesses located above the tray carrying the molds, the transfer tray having a series of recesses which carry individual vehicles for transporting molded blanks out of the compression drum, the succession of operations of the drum comprising, in sequence, the filling of a mold by its proportioner, the introduction of the needle into the mold, compression molding of the blanks, and transfer of the blank to a vehicle in the transfer tray, all of the operations being controlled and synchronized by the rotation of the drum.

5. A system according to claim 3, in which the machining drum comprises a rotary tray provided with a series of recesses to receive the insulator blanks, carried in individual vehicles, a machining mill with a contour which is complementary to the contour to be given to the insulator blank, a machining tray, integral with but axially displaced from the tray carrying the vehicles, a series of support needles, one for each recess and each movable, with respect to the mill, between a position coaxial with the axis of the corresponding recess, for removing a blank from and returning the blank to its vehicle, the movement of the needles with respect to the mill being controlled by the rotation of the drum, thereby insuring that the milling operation is carried out progressively, and driving means for rotating the blank about its axis, during the milling operation, all the movements being controlled by the rotation of the drum, while the mill, which is coaxial with the drum, rotates at a speed which is different from that of the drum.

6. A system according to claim 2, in which the sintering means comprises at least one curing tunnel through which the machined insulators pass, the curing tunnel being followed by at least one cooling area and a sintering transfer means which passes the insulators through the curing tunnel and the cooling area.

7. A system according to claim 6, in which the sintering transfer means comprises a series of refractory vehicles each adapted to carry one insulator, an endless conveyor which carries the refractory vehicles through a plurality of curing tunnels and the cooling area, a loading drum, and an unloading drum, the endless conveyor cooperating with the unloading drum to effect the reverse operation of the loading drum at the exit of the cooling area, the curing tunnels being preceded by a distributor and the cooling area being followed by a line combiner which respectively divides the line of refractory vehicles carrying the insulators into a predetermined number of parallel lines passing through the

curing tunnels and the cooling area, these parallel lines being re-combined into a single line on emerging from the cooling area.

8. A system according to claim 1, in which the component-assembly station comprises a central component assembly machine for performing the insertion operations, and in which the assembled components are exchanged between the assembly machine and the curing means by a transfer made in continuous kinematic motion.

9. A system according to claim 8, in which the central component assembly machine comprises a unit for introducing the insulators, a rotary unit for marking and enamelling, a unit for introducing an electrode into each insulator, a unit for supplying the cement and compacting it into the insulator around the electrode, and a unit for introducing an electrical connection rod into each insulator in engagement with the cement, each unit comprising at least one drum, and the units exchanging the assembled parts in continuous kinematic motion.

10. A system according to claim 9, in which the unit for introducing the insulators comprises a plurality of distributor tubes through which the insulators pass one after the other, each tube terminating above an introducing drum, two separators revolving synchronously with the introducing drums and at each turn distributing an insulator above a relevant recess in the drum which carries a vehicle ready to receive an insulator, each introducing drum depositing an insulator in only one vehicle out of a predetermined number K, where K is the total number of introducing drums in series.

11. A system according to claim 9, in which the marking unit includes a marking drum which comprises a marking tray having a series of recesses for receiving vehicles each carrying one insulator, a printing drum, a lower tool for releasing each insulator from its vehicle and engaging the insulator in an upper tool, and a needle engageable in a central aperture in the insulator, the accessory formed by the upper tool and the lower tool being driven rotatively by a marking pad carried by the printing drum, the axis of which is fixed and occupies a satellite position with respect to the axis of rotation of the marking tray, the printing drum carrying the printing pads on its periphery of its revolving tray and rotating synchronously with the marking tray so as to bring each insulator and each marking pad into contact when the marking drum is rotating, the printing operation being carried out by contact without substantial friction, and the insulator being returned to its vehicle after the printing operation.

12. A system according to claim 9, and further comprising an enamelling drum including an enamelling tray having a series of recesses each receiving a vehicle carrying an insulator, a lower tool, and a plurality of enamelling nozzles, the lower tool releasing the insulator from the vehicle and supporting the insulator for an enamelling operation, the lower tool being driven rotatively with respect to the enamelling tray that carries it, the enamelling nozzles being integral with the enamelling tray opposite each insulator in the free position and a pneumatic distributor revolving with the enamelling drum and pumping varnish into a storage vessel, the insulator being returned to its vehicle upon completion of the enamelling operation.

13. A system according to claim 9, in which the unit for introducing electrodes into the insulators comprises

a distributor with guide rails bringing the electrodes to a level adjacent the axis of an electrode introducing drum, the electrode introducing drum comprising an insertion tray having a series of recesses for receiving a series of vehicles each carrying an insulator, a guide tray having radial corridors, coaxial with and rotatable with the insertion tray, each radial corridor starting at the center of the insertion tray and ending on the periphery at an aperture of a size greater than the greatest radial dimension of the electrode, and coaxial with each vehicle in a recess, the guide tray receiving the electrodes separately, by gravity, through a hub having a cavity cooperating with the forward end of the guide rails, and a fixed helix for guiding the heads of the electrodes to move them from the axis of the drum toward its periphery above the aperture of the respective radial corridor where the transfer of the electrode into the insulator is effected.

14. A system according to claim 9, in which the unit for introducing the cement comprises a cement storage hopper mounted for rotation with a cement dispensation drum, the bottom of the hopper having a series of supply orifices corresponding to a series of recesses in the drum, a non-rotating scraper engaging the bottom of the hopper, at the level of the orifices, to mask the orifices during a part rotational movement, and means for dispensing and packing cement comprising a piston movable in translation, partly introducing itself into each hopper orifice to define with the upper surface and the lateral surface of the orifice a volume Q corresponding to the amount of cement to be dispensed, the return movement of the piston dispensing the quantity Q of cement into the central aperture of each insulator, the piston also carrying a needle which, after the introduction of the cement into the insulator, is actuated to pack the cement, the movement of the piston and of the needle which it carries being controlled by fixed cams, during the rotation of the drum.

15. A system according to claim 1, in which the final assembly station comprises a unit for introducing a series of conductive holders and inserting into each holder a lower gasket, a drum for inserting an assembled central component into each holder, a distributing unit for inserting an upper gasket into each holder, a unit for compacting and crimping each holder against the associated central component, a unit for mounting a connection nut on each central component, electrode adjustment and checking drums, a drum for placing a cylinder head gasket into position on each holder, a drum for testing dielectrically the whole of the operations and transfers effected in continuous kinematic motion, and each of the units comprising at least one drum, with all of the drums being mounted interchangeably.

16. A system according to claim 15, in which the holder introducing unit comprises a holder distributor feeding a first drum for introducing the holders and a distributor of lower gaskets, feeding a second drum for receiving the holders from the first drum, for placing a lower gasket into position on each holder.

17. A system according to claim 15, in which the compacting and crimping unit comprises a compacting drum which receives a series of assemblies each comprising a holder, a lower gasket, a central component and an upper gasket, and which compacts this assembly, a cold crimping drum for subsequently crimping the holder to the central component, a heating drum

for heating the cold-crimped holder, and a hot crimping drum for subsequently crimping the heated holder

18. A system according to claim 17, in which the compacting drum comprises a tray having a series of recesses for receiving the assemblies, a lower tool supporting each assembly by the holder during the compacting operation, and an upper tool which comes to bear on the upper gasket of the assembly with a calibrated force, all these operations being controlled by fixed cams, during the rotation of the compacting drum.

19. A system according to claim 17, in which the cold and hot crimping drums each comprise a rotary tray having a series of recesses for receiving the assemblies to be crimped, a lower tool for supporting the holder of the assembly during the crimping operation, and an upper tool exerting a calibrated force on the edge of the holder to crimp it, the various movements being controlled by fixed cams, during rotation of the drum.

20. A system according to claim 15, in which the unit for distributing the electrical connection nuts comprises a distributor which orients the nuts and a device for bringing the nuts above a distribution and screwing drum comprising movable components which seize the nuts in flight and make them slide along a ramp and fall

onto the threaded end of the connecting rod, by cooperating with a guide needle constituting an upper tool, the guide needle entering the upper orifice of the nut and, when the latter is in position, coming onto the threaded end and tightening the nut by rotation.

21. A system according to claim 15, in which the unit for placing each of the lower, upper and cylinder head gaskets into position, comprises a central rotary tray having a series of recesses carrying the assemblies which are to receive the gaskets, a guide ramp bringing the gaskets in a line following the periphery of the circular course of the assemblies, an upper tool, including a needle, corresponding to each recess, for catching each gasket in flight, driving the gasket along the ramp and dropping the gasket into position on the assembly.

22. A system according to claim 15, including a seal test drum comprising a vertically movable pusher, which pushes each spark plug into a cavity in which a predetermined pressure is produced by passing compressed air into the cavity through a check valve, the whole being connected to a pressure multiplier actuated by the movement of the seal test drum, any seal defect of the spark plug being detected by a manometer which causes the defective spark plug to be ejected.
